United States Patent

Des. 239,932
Patented May 18, 1976

239,932

REARVIEW MIRROR

Myung S. Kim, 2900 Knights Road, Room B-15,
Cornwell Heights, Pa. 19020

Filed Mar. 12, 1975, Ser. No. 557,588

Term of patent 14 years

Int. Cl. D12—16

U.S. Cl. D12—187

FIG. 1

FIG. 2

FIG. 3

FIG. 4

FIG. 5

FIG. 1 is a front elevational view of a rearview mirror;
FIG. 2 is a top plan view thereof;
FIG. 3 is a right side elevational view thereof;
FIG. 4 is a rear elevational view thereof; and
FIG. 5 is a bottom plan view thereof.

I claim:

The ornamental design for a rearview mirror, as shown.
